CLAIM

We claim the ornamental design for countertop deep fryer, as shown.

DESCRIPTION

FIG. 1 is a front perspective view of a countertop deep fryer according to the first embodiment of the invention.

FIG. 2 is a front, elevational view of the countertop deep fryer of FIG. 1.

FIG. 3 is a rear, elevational view of the countertop deep fryer of FIG. 1.

FIG. 4 is a right side elevational view of the countertop deep fryer of FIG. 1.

FIG. 5 is a left side elevational view of the countertop deep fryer of FIG. 1.

FIG. 6 is a top view of the countertop deep fryer of FIG. 1.

FIG. 7 is a bottom view of the countertop deep fryer of FIG. 1.

FIG. 8 is a front perspective view of a countertop deep fryer according to the second embodiment of the invention.

FIG. 9 is a front, elevational view of the countertop deep fryer of FIG. 8.

FIG. 10 is a rear, elevational view of the countertop deep fryer of FIG. 8.

FIG. 11 is a right side elevational view of the countertop deep fryer of FIG. 8.

FIG. 12 is a left side elevational view of the countertop deep fryer of FIG. 8.

FIG. 13 is a top view of the countertop deep fryer of FIG. 8; and,

FIG. 14 is a bottom view of the countertop deep fryer of FIG. 8.
